UNITED STATES PATENT OFFICE

EDWIN REYNOLDS, OF VINELAND, NEW JERSEY

DESIGN FOR A TEMPLE MEMBER FOR SPECTACLES

Application filed May 2, 1932. Serial No. 43,694. Term of patent 14 years.

To all whom it may concern:

Be it known that I, EDWIN REYNOLDS, a citizen of the United States, residing at Vineland, in the county of Cumberland and State of New Jersey, have invented a new, original, and ornamental Design for a Temple Member for Spectacles, of which the following is a specification, reference being had to the accompanying drawing, forming part thereof.

The figure is a perspective view of a temple member for spectacles showing my new design.

I claim:

The ornamental design for a temple member for spectacles, substantially as shown.

EDWIN REYNOLDS.
